CIGARETTE CASE WITH SPRING FOLLOWER

George Breitwieser, Flushing, N. Y.

Application June 18, 1947, Serial No. 755,361

2 Claims. (Cl. 206—41.2)

1

This invention relates to a cigarette case. The object of the invention is to provide a cigarette case, in which a plurality of cigarettes are contained, and from which one may be conveniently extracted, upon which the others are disposed in such a manner to readily extract or discharge the next cigarette.

The invention consists of a casing shaped to hold a number of cigarettes, say about ten, with a discharge opening at one end and means within the casing for discharging the cigarette beneath said opening, the remaining cigarettes being subjected to a pressure from a spring which is placed in pressure position by a slideable sleeve, and which spring has a self contained inherent resiliency, which when once disposed into operative position serves to use up its tension until all of the cigarettes have been discharged, whereupon it is necessary to again dispose the spring into operative position.

The invention will be further described, an embodiment thereof shown in the drawings, and the invention will be finally pointed out in the claims.

In the accompanying drawings,

Fig. 1 is a perspective view of the improved cigarette container, in phantom form to show the improved spring;

Fig. 2 is a vertical section taken on line 2—2 of Fig. 1;

Fig. 3 is a bottom view of Fig. 2;

Fig. 4 is a horizontal detail section taken on line 4—4 of Fig. 2;

Fig. 5 is an end view of Fig. 2;

Fig. 6 is a detail section taken on line 6—6 of Fig. 2, and;

Fig. 7 is a vertical end view of the cigarette pusher as seen from line 7—7 of Fig. 2, and

Fig. 8 is a diagrammatic drawing of the spring action.

Similar characters of reference indicate corresponding parts throughout the various views.

Referring to the drawings, the casing 10 is of general rectangular shape, having a top 11, a bottom 12, side walls 13 and 13a, and end walls 14 and 14a.

Within the casing 10 is a spring 15, comparable to a watch spring, which has one end 15a hinged to a pusher 16, formed of two cigarette embracing members 17 and 17a, and intermediate brackets 18, which support a rod 19 to which rod 19 the spring 15 is suitably secured, preferably by bending it into loop shape and securing the end to the main portion. Preferably a weight 19a is suitably secured to the lower member 17a. The spring 15 then extends downwardly towards the bottom 12 of the casing 10, in slightly curved

2

form and terminates at the further end 15a of the casing 10, where it is secured to the bottom 12. This is done preferably by having the end of the spring 15 enter a slot 21 in the bottom, and then held in fixed position by a solder 22 (Fig. 2).

A sleeve 25 surrounding the spring 15 serves to place the spring 15 into tension position, that is to the full line position shown in Fig. 2. The sleeve 25, after enclosing the spring 15, has divergent extensions 26 (Fig. 6), which act as a guide to move on opposed tracks 27 formed by the bottom 12, these tracks being spaced from each other to form a slot 28. To these extensions, there is secured a lip 29, the flanges 30 of which move along the bottom of the tracks (Figs. 2 and 6).

This sleeve 25 is moved into the position shown in full lines in Fig. 2 whereby the brackets 18 which serve as a plunger or pressure member are in a position to act on the adjacent cigarette or a charge, of say, 9 cigarettes, whereby all of the cigarettes are under pressure to the end of placing the furthest cigarette into discharge position. The sleeve 25 is then returned to its initial position close to the end of the casing, as shown in dotted lines in Fig. 2, whereby the spring exerts its pressure upon the cigarettes until the last one has been discharged.

The discharge of a cigarette is made possible by a step 35 aligned with the bottom end of the cigarette, which end is flush with the top of two parallel ridges 21a (Fig. 2). The step 35 has an upwardly extending member 36, bent at its upper end 36a secured to a decorative handle 37 of plastic or the like. A slot 37a in the end 36a permits movement of the end 36a. A helical spring 38 seats at one end against this bent portion, and presses it downwardly. The other end of the spring 38 presses against a bent portion 39 of a guiding member 40. This member 40 has a slot 40a to permit the passage of the step 35, and the two legs 41 thus formed have their lower ends formed into tongues 42 to engage slots 43 in the bottom 12, and then upset, and preferably soldered (Fig. 3). An inside plate 31b is secured to the member 36, and moves with it, up or down to cover the slot on the inside. Ridges 15a on the inside of the walls serve to stiffen the walls and guide the cigarettes. The wall 11a serves to prevent the spring abutting against the cigarette.

The top 11 is hinged at one end at 44, and has a detachable clasp 45 at its other end. A shutter 46 having its sides bent over the top slides between two abutments 47 and 48, between which the top has the opening 50, slightly larger than the circumference of a cigarette 51. The shut-

55

ter 46 is shown in its open position in Fig. 1, and in its closed position in Fig. 2.

When the case is empty, the cover 11 is opened and a charge of cigarettes is disposed therein, the sleeve 25 having first been moved from its right hand to its extreme left hand position (Fig. 2). The end cigarette of the charge is then placed against the braces 17 and 17a, and the spring is tensioned, by moving the sleeve 25 from its left hand to its right hand position.

When the user desires to use a cigarette, he merely pushes the shutter 46 to expose the opening 50. The button 31 is then moved to raise the step 35, and the cigarette on the step is then pushed upwardly to have its end project from the casing 10, and ready to be grasped and drawn out by the user. The shutter is then again moved to close the opening 50. The braces 17 and 17a then keep on pressing the remaining cigarettes of the charge, and align the next cigarette below the opening 50, so that the one over the step 35 is ready to be partially projected when desired, as described.

Finally, in the embodiment, the ridges 27a incline upwardly at 27b, and raise the end cigarette slightly. The brace 17 has a bent up projection 17b, which may abut against the spring, so as to prevent the brace 17 from moving over too far. This projection 17b causes the braces counterbalanced by the weight 19, to always be in a position to abut against the vertical position of the cigarette.

The spring 15 when placed under tension into the position shown in Fig. 2 in full lines, is allowed to work out its release from tension as the cigarettes are individually removed. While the slide 25 is shown in full lines in Fig. 2, in which position it places the spring 15 under its operative tension, it is to be understood that the slide is immediately moved from left to right to its extreme right hand position, where the slide 25 abuts against the end of the slot 28. This end position of the slide 15 is shown in Fig. 8. The spring 15 is thus free to work under its own law of operation as shown diagrammatically in Fig. 8. After the last cigarette has been discharged, the slide 25 is then moved into its full line position as shown in Fig. 2, the cover 11 is opened, a charge of cigarettes is placed into the casing, the cover is closed, and the slide immediately moved to its position as shown in Fig. 8.

I have described several forms of my invention, but obviously various changes may be made in the details disclosed without departing from the spirit of the invention as set out in the following claims:

I claim:

1. In a cigarette holder, the combination of a plurality of cigarettes, a casing for holding said cigarettes in a vertical position one parallel with the other having two end and a plurality of intermediate cigarettes when filled, one end cigarette being a discharge cigarette and the other end cigarette being a pressure cigarette, a top wall above said cigarettes perpendicularly disposed to the longitudinal axes of said cigarettes, and having an opening above the discharge cigarette for the discharge of said end cigarette from the casing, a bottom wall below said cig-

arettes and parallel with the top wall, a spring of flat shape having one end secured to the bottom wall substantially below the discharge opening in the top wall, and having a main portion of the length of said bottom wall with a part extending in curved form upwardly from said bottom wall and towards the pressure cigarette, said spring forming a tension activating circular partial convolution in a vertical plane passing through the vertical axes of the cigarettes and of such resiliency as to exert a pressure upon the pressure cigarette until the cigarettes have been discharged, a brace pivoted to the free end of the spring to abut against the pressure cigarette, and means holding the spring from exerting pressure on said brace, and holding the extending part with its brace in a temporary stationary position at the end of the casing opposite to its discharge end for filling cigarettes between said brace and the discharge end of the casing, said holding means when released, enabling the spring to exert its resiliency upon said brace from the cigarette filled position to cigarette discharged position.

2. In a cigarette holder having a casing, the combination of a false bottom wall for said casing having a longitudinal slot, and forming a guide rail, a sliding member movable along said slot on said guide rail, said slot extending substantially the length of the casing, a spring of flat shape of the general character of a watch spring and normally coiled to almost a circular shape for tensing activation and of greater length than the slot, the length of the spring corresponding to the length of the slot being the main part and disposed in a plane longitudinally perpendicular to the false bottom, said main part having one end secured to one end of the bottom wall, said sliding member embracing said spring for moving the main part, when the sliding member moves along said slot, from its circular shape activated position into a position flattened along the length of said false bottom inactivating the said main part of the spring, said main part having an extension beyond said sliding member when the sliding member is at the spring inactivating position.

GEORGE BREITWIESER.
